FILLING SPOUT

Edric W. Vredenburg, Berkeley, Calif.

Original application September 26, 1939, Serial No. 296,579. Divided and this application August 4, 1942, Serial No. 453,508

2 Claims. (Cl. 226—18)

This application is a division of my application Serial No. 296,579, filed September 26, 1939, now Patent Number 2,314,299, dated March 16, 1943.

This invention relates to filling spouts, particularly those employed in conjunction with weighing-feeder mechanisms for the filling of bags and the like. In the weighing out of small unit quantities of various bulk commodities such as flour, sugar, salt, beans, candy and the like, it is essential that the transfer of materials into the container be effected quickly and without loss of the materials fed and weighed. The filling spout of this invention is particularly suited to such use.

It is generally the broad object of the present invention to provide a novel form of filling spout to enable bulk materials to be fed, weighed and rapidly discharged into suitable containers such as a bag or the like. The spout of this invention also facilitates the opening and the proper positioning of a container to receive material from the spout.

The invention includes other objects and features of advantage some of which, together with the foregoing will appear hereinafter wherein the present preferred form of spout of this invention is disclosed.

In the drawing accompanying and forming a part hereof Figure 1 is a side elevation of the filling spout of this invention.

Figure 2 is a side elevation, partly in section, taken along the vertical section line shown in Figure 1.

A typical down spout of a suitable feeder-weighting mechanism is indicated generally at 6. This down spout, usually in the form of a frustum of a cone is shown as terminating in a terminal ring 7. The down spout 6 is usually made of a light sheet metal and the ring 7 serves to reinforce it. The bag filling spout of this invention is indicated generally at 8. It comprises a first member 9 and a second member 11. The first member 9 is secured to the terminal ring 7 and is usually fixed in position. It depends from the terminal ring 7 with the outer face thereof arcuately formed and flowing smoothly down to a terminal lip at 12 provided along the lower edge thereof. The inner terminal edge 14 of member 9 slants outwardly and away from a vertical plane indicated generally by line 15—15. The reason for this will become further apparent in connection with the detailed disclosure of member 11, which is hinged at its upper end on suitable screws 16 which extend into the ring 7.

The forward edge 19 of member 11 slopes outwardly, away from the member proper and beyond the vertical plane represented in Fig. 1 by the line 15—15, to fit snugly against terminal edge 14 and lip 12 on member 9. In addition, member 11 includes a portion 18 thereof which extends outwardly away from the hinge provided by screws 16 so that member 11 is biased to engage the terminal edge 14 and the terminal lip 12 on member 9. This ensures a quick and adequate closure for the down spout and any material therein.

In use, an operator engages extension finger 17 provided upon the ring 7 to steady the down spout-filling spout structure, because this is usually mounted upon some type of movable weighing frame. A bag or other container is then partially opened and drawn into position. Conveniently the size of the bag employed can be such that it fits snugly about members 9 and 11 so that when these are moved apart the bag is fully opened and retained in position until such time as the material is completely fed into the bag. Or, if desired, the bias provided upon member 11 can be such that the material is retained and held until such time as it is released by an operator engaging extension 18 on member 11 and rocking the member about its hinge. Member 11 can also be biased by means of a spring toward closed position.

I claim:

1. In combination, a downspout, a bag filling spout, said bag filling spout comprising a first and a second member, said first member being fixed on said downspout and extending below the terminal end of said downspout, said first member having its outer depending wall of arcuate section and extending substantially vertically to provide a relatively thin, flat member with an arcuate terminal lip, the edges of said terminal wall extending inwardly at an angle to a plane passed vertically through an upper portion of said member to provide said terminal lip at a distance spaced from said vertical plane, said second member being hinged on said downspout and having an outer depending wall of arcuate section, the radii of both said wall arcuate sections being relatively great so that said sections when closed provide cooperatively an element adapted readily to enter and open an end of a paper bag positioned for filling, said second member being hinged substantially on said vertical plane and having a substantial portion thereof normally lying on that side of said vertical plane which is adjacent to the first member and complementary

to said first member to provide a closure for said downspout.

2. In combination, a downspout, a bag filling spout, said bag filling spout comprising a first and a second member, said first member being fixed on said downspout and extending below the terminal end of said downspout, said first member having its outer depending wall of arcuate section and extending substantially vertically to provide a relatively thin, flat member with an arcuate terminal lip, the edges of said terminal wall extending inwardly at an angle to a plane passed vertically through an upper portion of said member to provide said terminal lip at a distance spaced from said vertical plane, said second member being hinged on said downspout and having an outer depending wall of arcuate

section, the radii of both said wall arcuate sections being relatively great so that said sections when closed provide cooperatively an element adapted readily to enter and open an end of a paper bag positioned for filling, said second member being hinged substantially on said vertical plane and having a substantial portion thereof normally lying on that side of said vertical plane which is adjacent to the first member and complementary to said first member to provide a closure for said downspout, said second member having a portion of its outer wall extending upwardly to a point above a horizontal plane passed through said hinge to provide a bias on said second member toward closed position.
